CABINET FOR AN ELECTRONIC CONTROL UNIT

William E. Pascale, San Jose, and Jack W. Stringer, Los Gatos, Calif., assignors to International Business Machines Corporation, Armonk, N.Y., a corporation of New York

Filed Dec. 6, 1965, Ser. No. 87

Term of patent 14 years

(Cl. D26—5)

FIG. 1

FIG. 2

FIG. 3

FIG. 1 is a front perspective view of a cabinet for an electronic control unit showing our new design, the rear being substantially plain and unornamented;

FIG. 2 is a top plan view thereof;

FIG. 3 is an enlarged view of the control panel shown in FIG. 1.

The characteristic feature of our design resides in the appearance and arrangement of the several panels forming the front thereof as best shown in FIG. 1.

We claim:

The ornamental design for a cabinet for an electronic control unit, as shown and described.
